(57) **CLAIM**

The ornamental design for a wallet with twist fold open, as shown and described.

DESCRIPTION

FIG. 1 is a perspective view of a wallet with twist fold open; FIG. 2 is a front view of a wallet with twist fold open; FIG. 3 is a back view of a wallet with twist fold open; FIG. 4 is a right side view of a wallet with twist fold open; FIG. 5 is a left view of a wallet with twist fold open; FIG. 6 is a top view of a wallet with twist fold open; FIG. 7 is a bottom view of a wallet with twist fold open; FIG. 8 is an open view of a wallet with twist fold open; and, FIG. 9 is a twisted view of a wallet with twist fold open. The evenly dashed broken lines in the drawings depict stitching of the wallet that form part of the claimed design. In addition, the dash-dot-dash broken lines depict portions of the article that form no part of the claimed design.
